UNITED STATES PATENT OFFICE

2,536,416

BOX LIDDING MACHINE

Harry D. Benson, Fresno, Calif., assignor to General Nailing Machine Corporation, Sanger, Calif., a corporation of California

Application June 2, 1947, Serial No. 751,741

13 Claims. (Cl. 1—10)

1

This invention is directed to, and it is an object to provide, an improved, automatic nailing machine for boxes, particularly of the type used for transporting fruit and vegetables.

While the machine is generally adaptable for other box nailing operations, it is here shown as adapted for nailing lids on boxes; the provision of a novel lidding table assembly being another object of the invention.

An additional object of the present invention is to provide a nailing machine, as in the preceding paragraph, in which the lidding table assembly includes an endless chain feed for boxes, the latter resting on the upper runs of the transversely spaced chains of said feed, and said runs being yieldably supported to permit of limited downward movement of each box into engagement, at the bottom adjacent the ends, with rigid stop bars for the lid nailing operation.

A novel lid holder and aliner is associated with the lid nailing units, and functions to aline the lid and box in advance of said lid nailing operation.

A further object of the invention is to incorporate, in the nailing machine, a novel, adjustable mounting frame for the box supporting units, and box nailing units; such frame including a pair of transversely spaced, vertical posts to which the units are attached, and the posts being mounted for guided lateral adjustment, without in any way disturbing the setting of said attached units, to adjust the machine for different length boxes. Thus, as the box engaging working parts move in unitary relation with the posts, the machine can be adjusted readily and easily.

It is also an object of this invention to provide an adjustable mounting frame, as in the preceding paragraph, which includes therein a vertically reciprocable, horizontal, top driving bar; the posts being vertically slotted for the guiding reception of said driving top driving bar, and the box nailing units being laterally adjustably attached to, and actuated by said top driving bars and slideable on said slotted posts.

Another object of this invention is to provide a box nailing machine, wherein said adjustable mounting frame is designed so that box engaging working parts, such as the lidding table assembly, may be removed conveniently, and other types of working parts, such as a box framing assembly, substituted. Thus, the machine is convertible for numerous different box nailing operations.

A further object of the invention is to produce a practical device and one which will be exceedingly effective for the purpose for which it is designed.

2

These objects are accomplished by means of such structure and relative arrangement of parts as will fully appear by a perusal of the following specification and claims.

In the drawings:

Figure 1 is a front elevation of the machine.

Figure 2 is a fragmentary perspective view partly in section and taken generally along a line 2—2 of Fig. 1, showing the upper end position of one of the vertically slotted posts and its relation to the adjacent and cooperative parts of the mounting frame at the top.

Figure 3 is a fragmentary perspective view partly in section and taken generally along a line 3—3 of Fig. 1, without the drive shaft and chain, and showing the lower end portion of one of the vertically slotted posts and its relation to the adjacent and cooperative parts of the mounting frame at the bottom.

Figure 4 is a fragmentary sectional elevation of one of the lid nailing units traveling downward toward but short of nailing position.

Figure 5 is a similar view but shows said lid nailing unit in nailing position.

Figure 6 is a view looking in the direction of the arrows on line 6—6 of Fig. 1 and showing a fragmentary, face elevation of one of the lid nailing units, including the lid holder and aliner.

Figure 7 is a fragmentary sectional plan of a portion of said lid nailing unit.

Figure 8 is a view looking in the direction of the arrows on a line 8—8 of Fig. 1 and is a fragmentary elevation showing one of the lidding table units.

Figure 9 is a cross section on line 9—9 of Fig. 8.

Figure 10 is a cross section taken generally on a line 10—10 of Fig. 8 but showing the carrying chain depressed into a position substantially flush with the nailing table bar.

Fig. 11 is a fragmentary sectional view taken on a line 11—11 of Fig. 6.

Fig. 12 is a fragmentary sectional view taken on a line 12—12 of Fig. 8.

Fig. 13 is a fragmentary sectional view taken on a line 13—13 of Fig. 6.

Fig. 14 is a fragmentary elevation of one of the legs of the main frame, showing the connection of the transverse bottom bars therewith.

Referring now more particularly to the characters of reference on the drawings, the improved nailing machine comprises a main frame, indicated generally at 1, which main frame is of fabricated sheet metal including transversely spaced, hollow legs 2 connected at the upper end

by a top beam 3, and connected at the bottom by a hollow base housing 4.

The main frame 1 thus defines a substantially rectangular opening 5 in which the box engaging working parts of the machine are disposed in the manner hereinafter described in detail.

Mainly within the opening 5 the machine includes an adjustable mounting frame, indicated generally at 6, which mounting frame carries a pair of transversely spaced lid nailing units 7, and therebelow a pair of corresponding lidding table units 8. The top beam 3 of the main frame 1 supports a power actuated nail stripper 9 which feeds nails through flexible tubes 10 to the lid nailing units 7; the nail stripper 9 and its feeding tubes 10 being substantially conventional.

The lid nailing units 7 are vertically actuated or reciprocated by a horizontal top driving bar 11 included, in vertically reciprocable relation, in the mounting frame 6, and said top driving bar 11 is actuated one complete cycle at a time from a normally raised starting position by connecting rods 12 secured to opposite ends of said bar and depending within the hollow legs 2 of the main frame 1. Such connecting rods 12 have dashpot-like shock absorbing means included therein and are connected, at their lower ends, to cranks 13 on a cross shaft 14 journaled within the hollow, base housing 4 of the main frame 1. An electric motor 15 is mounted in the base housing 4 and, through the mechanism of a clutch and brake unit, indicated generally at 16, is adapted to rotate the cranks 13 through only a full circle upon each depression of a control pedal 17. The operator steps on the pedal 17, and the clutch and brake unit 16 then function to impart one revolution only to the cranks 13, which in turn, working through the connecting rods 12, reciprocate the top driving bar 11 through one cycle, starting from its top position, and actuating the lid nailing units 7.

The above comprises the general assembly of the machine, and there is now described the details of the adjustable mounting frame 6, together with the lid nailing units 7 and lidding table units 8.

The adjustable mounting frame 6 includes a pair of transversely spaced vertical posts 18 vertically slotted, as at 19. At their lower ends the posts 18 as shown in Figs. 1 and 3 are attached in guided and laterally adjustable relation to a fixed bottom bar assembly including a pair of horizontal, transversely extending bottom bars 20 disposed in spaced-apart relation and connected to the frame legs 2 as shown in Fig. 14. At its lower end each post 18 includes a U-shaped, downwardly opening yoke 21 straddling the bottom bars 20 transversely thereof, with the legs of such yoke bearing on the outer faces of such bars. Guide feet 22 are fixed to the yoke 21 in a manner to slidably bear against adjacent faces of the bars 20; one of the guide feet 22 being elongated and including an inverted L-shaped guide finger 23 engaging over the adjacent one of said bars 20. With this arrangement the posts 18 are adjustable, at the bottom, along the assembly of bars 20, in accurately guided relation. Normally, however, said posts 18 are fixed against sliding motion relative to the bars 20 by reason of the fact that one leg 24 of the U-shaped yoke 21 is a separate element secured by a bolt 25; tightening of which bolt releasably clamps the yoke 21 in a fixed position.

The top driving bar 11 is vertically slotted lengthwise thereof, as at 26, and said top bar pro-

jects, in guided relation, through the slots 19 of the posts 18 in vertically reciprocable relation.

At its end portions, and within the hollow legs 2, the top driving bar 11 projects in guided, and also vertically reciprocable, relation, between pairs of upstanding guide bars 27. Outwardly of each pair of guide bars 27 the top driving bar 11 is fixed with an end plate 28, which bears in guided relation against the bars 27, and it is to these end plates 28 that the connecting rods 12 are attached at their upper ends. See Figs. 1 and 2.

Each of the lid nailing units 7 is of identical construction, and therefore a description of one will suffice for both. This construction is shown in Figs. 1, 2 and 4-6.

Each lid nailing unit 7 comprises an upper cross bar 29 attached to the under side of the top driving bar 11 by a bolt 30 which passes through the slot 26 in said top bar.

The upper cross bar 29 is disposed laterally inwardly relative to the corresponding posts 18, and secured to the outer face thereof are bearing blocks 31 running on the adjacent faces of said post 18. Also secured to the outer face of the bar 29 by welding or other means is a locator block 32. This block 32 is shown in Figs. 4 and 5 and projects through the space 19 in the post 18 with a close running fit therein and is held in position by a strap 33 which is bolted or otherwise secured to block 32 and which strap bears on the outer face of the post 18. The locator block 32 also has a portion 32a which fits closely in the slot 26 of the top driving bar 11.

A lower cross bar 34 is disposed some distance horizontally below the upper cross bar 29 and slightly closer to the adjacent post 18; said lower cross bar 34 having a guide block 35 fixed thereto centrally of its ends, and said guide block 35 runs in the slot 19 of the post 18. The lower cross bar 34 and the guide block 35 are suspended from the locator block 32 by a suspension rod 36 fixed to the guide block 35, extending slidably through the locator block 32 and having a head 37 above said locator block. The rod 36 thus normally suspends the lower cross bar 34 a predetermined distance below the upper cross bar 29.

The guide block 35 is held against escape from the post slot 19 in one direction by the lower cross bar 34, and in the opposite direction by a cross strap 38 bearing on the opposite side of the post 18. The cross strap 38 is formed, at opposite ends, with circular seats 39 on which vertical shafts 40 are secured; said vertical shafts running through vertical sleeves 41 on opposite ends of the cross strap 38. Compression springs 42 surround the shafts 40, normally urging the cross strap 38, guide block 35, and lower cross bar 34 downwardly to the limit allowed by the suspension rod 36.

A plurality of nailing chucks 43 are fixed on the lower cross bar 34 in predetermined and adjustably spaced relation; the nail tubes 10 leading to corresponding ones of said chucks 43. Nailing or hammer rods 44 upstand from each chuck 43 in vertically reciprocable relation, and are connected, at their upper ends, to the upper cross bar 29 by annularly slotted, cylindrical heads 45 engaging in a bottom slotted channel on said upper cross bar 29.

With each reciprocation or cycle of the top driving bar 11, the lid nailing units 7 initially travel downwardly with their parts in the relative positions of Fig. 4 until the chucks 43 bear on the box, 75 as will hereinafter more fully appear. Thereafter,

with continued downward motion of the top driving bar 11 the chucks remain stationary and the shafts 40 slide through the sleeves 41, compressing the springs 42, and driving the nailing rods 44 downwardly in the chucks 43, as shown in Fig. 5, to accomplish a nailing operation. Upon the upward stroke of each cycle of the top driving bar 11, the parts of each lid nailing unit 7 return to their normal starting position.

Stops 47 in the slots 19 of posts 18 serve to limit downward travel of guide blocks 35 and chucks 43 when the machine is operated without a box therein.

Each of the lid nailing units 7 includes a depending lid holding and box alining plate 48 disposed below the lower cross bar 34 parallel thereto, and mainly below and somewhat laterally out relative to the nailing chucks 43.

At its upper edge the plate 48 is fixed to a horizontal shaft 49 journaled in brackets 49a secured to and depending from the cross bar 34 at its ends (see Figs. 1, 3 and 11) so that said plate is swingable transversely. A torque spring 50 is connected to the shaft 49 in a direction tending to rotate the shaft so as to swing the plate 48 away from the corresponding post 18. Spaced, rigidly mounted fingers 51 project inwardly at a downward slope between certain of the nailing chucks 43, and at their outer ends said fingers 51 carry a horizontal actuating rod 52 for the box aligning and lid supporting plate 48, which rod extends lengthwise of the direction of movement of boxes through the machine. The actuating rod 52 is upturned at its lead end, and includes a lid stop 53 at its opposite end, said actuating rod 52 normally extending in a horizontal plane somewhat below the lower ends of said nailing chucks 43.

Intermediate its upper and lower edges, and centrally of its ends, the plate 48 is fitted with an inwardly projecting, spring-pressed ball 54.

When the machine is in operation, initially separate box lids are fed, one at a time, into the machine, being disposed between the plates 48 of the lid nailing units 7, and releasably supported from below, at opposite ends, by the spring-pressed balls 54 preparatory to downward travel with said units 7 for nailing on top of a box then supported at opposite ends in the machine by the lidding table units 8, each of which comprises:

A horizontal nailing table bar 55 extends transversely of the corresponding post 18 laterally inwardly of the latter, and is fixed to a horizontal side plate 56 which extends in the same direction, i. e. lengthwise of the direction of movement of boxes through the machine. The side plate 56 is in turn fixed to a locator block 57 which includes a part extending, in locating relation, in the vertical slot 19 of said corresponding post 18. The locator block 57 is fitted with a back cap 58 which non-movably but adjustably clamps the locator block 57 to said corresponding post 18. In this manner the horizontal nailing table bar 55 is rigidly but adjustably attached to the corresponding post 18.

A downwardly yieldably mounted, chain supporting bar 59 extends alongside the horizontal nailing table bar; the upper edge of the bar 59 and the upper edge of the bar 55 normally being substantially flush. The chain supporting bar 59 is yieldably mounted by means of bolts 60 engaging through vertically elongated slots 61 in the bar 59; there being leaf springs 62 engaging said bar 59 from below and normally but yieldably

urging the same upwardly to the limit of its vertical motion as shown in Fig. 9.

The yieldably mounted bar 59 supports the upper run 63 of an endless chain 64 which turns about end sprockets 65 on opposite end portions of the bar 59; said endless chain 64 being sprocket driven from a cross shaft 66 below the units 8, and which cross shaft is constantly actuated from the motor 15 by means including an endless chain and sprocket unit 67.

An adjustable idler 64a, as shown in Fig. 8, maintains proper tension on the chain 64.

With the above arrangement it will be seen that the upper runs of the chains 63 of the lidding table units 8 normally run above the upper edge of the horizontal nailing bars 55.

When the machine is in operation, for lidding loaded boxes, the loaded boxes are fed, one at a time and by suitable means, onto the assembly 20 of lidding table units 8; each box 68, as it reaches the machine, resting at opposite ends on the upper runs 63 of the chains, and being fed into said machine thereby. When the box reaches a predetermined position below the lid nailing units 7, said box abuts against box stops 69 carried by the lidding table units 8 adjacent their discharge end and normally projecting into the path of box travel. Each stop 69 is mounted on a shaft 69a journaled in bearings 69b secured to the back plate 50. See Figs. 8, 9 and 12.

When each box 68 engages the stops 69 the upper runs 63 of the chains 64 slip under said box, and during the nailing operation.

As each box 68 comes to rest against the box 35 stop 69, the pedal 17 is depressed to cause a driving cycle of the top bar 11 and the lid nailing units 7.

A lid 70 has previously been engaged between the lid holding plates 48 and is supported by the spring-pressed ball 54, and such lid travels with 40 the nailing units 7. Lid stops 53, at the rear end of the actuating rods 52, locate each lid properly lengthwise of the direction of box travel in the machine. As the nailing units 7 reach the box 68, the nailing chucks 43 bear against the lid 70, 45 and the latter bears against the top edges of the ends of the box 68; the actuating rods 52 then having been urged upwardly somewhat, swinging the plates 48 toward each other sufficient to aline the ends of the box with the corresponding ends 50 of the lid. At this time the box 68 has also been depressed by the chucks 43, causing downward yielding of the upper chain runs 63 and the bars 59 from the position of Fig. 9 to the position of Fig. 10 until the box rests firmly at the bottom on 55 top of the horizontal nailing table bars 55.

With continued downward motion of the top driving bar 11, the nailing rods 44 drive through the nailing chucks 43 to penetrate the nails through the lid into the box end.

60 Rods 71 depend from the cross strips 33 of the nailing units 70, and slidably engage through sleeves 72 connected to actuating linkage 73 for corresponding box stops 69. A collar 74 on each rod 71 engages the corresponding sleeve 72 and 65 depresses it as the top driving bar 11 reaches the bottom of its stroke, and at which time the nailing operation is completed.

When the collars 74 engage and shift the sleeves 72 downward, the box stops 69 swing upwardly, 70 against the tension of torque springs 75, to a clearance position to permit of passage of the lidded box from the machine. These springs 75 are also compressible, being initially loaded or compressed when the box strikes the stops 69. 75 Thus, when the stops are swung upward, the

springs urge said stops rearward a limited distance but alongside the box. Thus, once the lidded boxes begin to travel, the stops 69 cannot return to stop position, by the torque of springs 75, until said lidded box is out of the machine.

The above described automatic nailing machine provides for the practical and convenient nailing of box parts; the machine being characterized by its novel adjustable mounting frame; the effective nailing units 7, including the lid holding and box lining plate assembly; and the novel lidding table unit assembly incorporating the downwardly yieldable chain supporting arrangement.

From the foregoing description it will be readily seen that there has been produced such a device as substantially fulfills the objects of the invention as set forth herein.

While this specification sets forth in detail the present and preferred construction of the device, still in practice such deviations from such detail may be resorted to as do not form a departure from the spirit of the invention as defined by the appended claims.

Having thus described the invention, the following is claimed as new and useful, and upon which Letters Patent are desired:

1. A box lidding machine comprising an upstanding main frame, an upstanding mounting frame on the main frame, transversely spaced vertically movable nailing units on the mounting frame, and transversely spaced work supporting table units on the mounting frame below and in cooperative relation to corresponding nailing units; said mounting frame including a pair of transversely adjustably spaced posts, and corresponding nailing and table units being attached to corresponding posts for adjustment therewith in unitary relation.

2. A box lidding machine comprising an upstanding main frame, an upstanding mounting frame on the main frame, transversely spaced vertically movable nailing units on the mounting frame, and transversely spaced work supporting table units on the mounting frame below and in cooperative relation to corresponding nailing units; said mounting frame including a horizontal bottom bar, a pair of transversely spaced posts upstanding from the bottom bar, and means transversely adjustably securing the posts adjacent their lower ends to the bottom bar, the nailing and table units being attached to corresponding posts for adjustment therewith in unitary relation.

3. A box lidding machine comprising an upstanding main frame, an upstanding mounting frame on the main frame, transversely spaced vertically movable nailing units on the mounting frame, and transversely spaced work supporting table units on the mounting frame below and in cooperative relation to corresponding nailing units; said mounting frame including a horizontal bottom bar, a pair of transversely spaced posts upstanding from the bottom bar, means transversely adjustably securing the posts adjacent their lower ends to the bottom bar, the nailing and table units being attached to corresponding posts for adjustment therewith in unitary relation, and a horizontal top driving bar mounted for vertical reciprocation and slidable relative to said posts, the nailing units being connected to said driving bar.

4. A box lidding machine comprising an upstanding main frame, an upstanding mounting frame on the main frame, transversely spaced vertically movable nailing units on the mount-

ing frame, and transversely spaced work supporting table units on the mounting frame below and in cooperative relation to corresponding nailing units; said mounting frame including a horizontal bottom bar, a pair of transversely spaced posts upstanding from the bottom bar, means transversely adjustably securing the posts adjacent their lower ends to the bottom bar, the nailing and table units being attached to corresponding posts for adjustment therewith in unitary relation, and a horizontal top driving bar mounted for vertical reciprocation, the posts being vertically slotted and the driving bar extending therethrough in slidable relation.

5. A box lidding machine comprising an upstanding main frame, an upstanding mounting frame on the main frame, transversely spaced vertically movable nailing units on the mounting frame, and transversely spaced work supporting table units on the mounting frame below and in cooperative relation to corresponding nailing units; said mounting frame including a horizontal bottom bar, a pair of transversely spaced posts upstanding from the bottom bar, means transversely adjustably securing the posts adjacent their lower ends to the bottom bar, corresponding vertically spaced nailing and table units being attached to corresponding posts for adjustment therewith in unitary relation, a horizontal top driving bar, the posts being vertically slotted and the driving bar extending therethrough intermediate its ends in slidable relation, and vertical guide means cooperating with opposite end portions of the driving bar, the nailing units being connected to and actuated by said driving bar.

6. A box lidding machine comprising an upstanding main frame, an upstanding mounting frame on the main frame, transversely spaced vertically movable nailing units on the mounting frame, and transversely spaced work supporting table units on the mounting frame below and in cooperative relation to corresponding nailing units; said mounting frame including a pair of horizontal bottom bars in parallel, an inverted U-shaped yoke on the lower end of each post straddling the bottom bars, one leg of each yoke being adjustable so as to releasably clamp said yoke to said bottom bars and longitudinal guide elements on the under side of the yoke between the bottom bars and bearing against adjacent faces thereof in post guiding relation.

7. A box lidding machine comprising an upstanding main frame, an upstanding mounting frame on the main frame, transversely spaced vertically movable nailing units on the mounting frame, and transversely spaced work supporting table units on the mounting frame below and in cooperative relation to corresponding nailing units; said mounting frame including a horizontal bottom bar, a pair of transversely spaced posts upstanding from the bottom bar, means transversely adjustably securing the posts adjacent their lower ends to the bottom bar, a horizontal top driving bar, means operative to power reciprocate the top driving bar through a vertical cycle, the posts being vertically slotted and the top driving bar extending therethrough intermediate its ends in slidable relation, the corresponding vertically spaced nailing unit and table unit being attached to each post below the top driving bar, and means connecting the top driving bar in operative relation to each nailing unit.

8. A box lidding machine comprising an up-

standing main frame, an upstanding mounting frame on the main frame, transversely spaced vertically movable nailing units on the mounting frame, and transversely spaced work supporting table units on the mounting frame below and in cooperative relation to corresponding nailing units; said mounting frame including a horizontal bottom bar, a pair of transversely spaced posts upstanding from the bottom bar, means transversely adjustably securing the posts adjacent their lower ends to the bottom bar, a horizontal top driving bar, means operative to power reciprocate the top driving bar through a vertical cycle, the posts being vertically slotted and the top driving bar extending therethrough intermediate its ends in slidable relation, the corresponding vertically spaced nailing unit and table unit being attached to each post below the top driving bar, each nailing unit including a cross bar releasably secured to the top driving bar for adjustment longitudinally thereof.

9. A box lidding machine comprising an upstanding main frame, an upstanding mounting frame on the main frame, transversely spaced vertically movable nailing units on the mounting frame, and transversely spaced work supporting table units on the mounting frame below and in cooperative relation to corresponding nailing units; said mounting frame including a horizontal bottom bar, a pair of transversely spaced posts upstanding from the bottom bar, means transversely adjustably securing the posts adjacent their lower ends to the bottom bar, a horizontal top driving bar, means operative to power reciprocate the top driving bar through a vertical cycle, the posts being vertically slotted and the top driving bar extending therethrough intermediate its ends in slidable relation, the corresponding vertically spaced nailing unit and table unit being attached to each post below the top driving bar, in each nailing unit including a cross bar releasably secured to the top driving bar for adjustment longitudinally thereof, the top driving bar being vertically slotted, and a locator block on the cross bar engaging in the slot of said top driving bar.

10. A box lidding machine comprising an upstanding main frame, an upstanding mounting frame on the main frame, transversely spaced vertically movable nailing units on the mounting frame, and transversely spaced work supporting table units on the mounting frame below and in cooperative relation to corresponding nailing units; said mounting frame including a horizontal bottom bar, a pair of transversely spaced posts upstanding from the bottom bar, means transversely adjustably securing the posts adjacent their lower ends to the bottom bar, a horizontal top driving bar, means operative to power reciprocate the top driving bar through a vertical cycle, the posts being vertically slotted and the top driving bar extending therethrough intermediate its ends in slidable relation, the corresponding vertically spaced nailing unit and table unit being attached to each post below the top driving bar, in each nailing unit including a cross bar releasably secured to the top driving bar for adjustment longitudinally thereof, the top driving bar being vertically slotted, a locator block fixed on the cross bar and projecting into the slot of the adjacent post from one side thereof, a cross strap affixed to the locator block on the opposite side of said post, and a portion of

said block engaging in the slot of the top driving bar in locating relation.

11. A box lidding machine comprising an upstanding main frame, an upstanding mounting frame on the main frame, transversely spaced vertically movable nailing units on the mounting frame, and transversely spaced work supporting table units on the mounting frame below and in cooperative relation to corresponding nailing units; each nailing unit being vertically reciprocated, and including a horizontal row of nailing chucks, laterally swingable lid holding and box lining plates disposed horizontally below and laterally out relative to said row of chucks, and means operative to swing the corresponding lid holding and box lining plates laterally inward as the nailing units lower in nailing relation to a box on said table units, said plates having a spring pressed lid holding element projecting laterally inwardly from the face thereof and adapted to receive and support a lid before the nailing units so lower.

12. A box lidding machine comprising an upstanding main frame including hollow sheet metal side legs in transversely spaced relation, an upstanding mounting frame within the main frame, said mounting frame including a horizontal bottom bar extending between said legs, a horizontal top driving bar extending between and projecting into said legs, said top driving bar being vertically reciprocable, a transversely spaced pair of posts mounted on the bottom bar and upstanding between said legs, said posts being arranged in guiding relation to the top driving bar, transversely spaced nailing units on the posts in vertically reciprocable relation and operatively connected to the top driving bar, work supporting table units on the posts below and corresponding to said nailing units, means within the legs guiding reciprocation of the top driving bar, and other means in the legs connected to opposite ends of the top driving bar and operative to reciprocate said top driving bar.

13. A box lidding machine comprising a support, a pair of vertically disposed posts mounted on the support in transversely spaced substantially parallel relation, the posts being adjustable transversely of each other along the support whereby to vary the space between the posts, a nailing unit mounted on each post for vertical sliding movement relative thereto, a work supporting table unit mounted on each post in vertically spaced relation to the nailing unit on such post, the nailing unit and the table unit on each post being both movable with the post to any adjusted position thereof relative to the other post, a driving bar mounted for vertical sliding movement relative to the posts and connected in driving relation with the nailing units, and means to reciprocate the driving bar.
